UNITED STATES PATENT OFFICE

153,679

DESIGN FOR A WRITING INSTRUMENT

Francis E. Gruber, St. Paul, Minn., assignor to
Brown & Bigelow, St. Paul, Minn., a corporation
of Minnesota

Application January 8, 1948, Serial No. 143,596

Term of patent 14 years

(Cl. D74—17)

To all whom it may concern:

Be it known that I, Francis E. Gruber, a citizen of the United States, residing in St. Paul, county of Ramsey, and State of Minnesota, have invented a new, original, and ornamental Design for a Writing Instrument, for which the following is a specification, reference being had to the accompanying drawings, forming part thereof.

Figure 1 is a front view of a writing instrument, showing my new design with writing point retracted.

Figure 2 is a side view thereof with the writing point in writing position.

Figure 3 is a view similar to Figure 1 with the barrel section separated and showing the ink reservoir as it appears when the pen is open.

I claim:

The ornamental design for a writing instrument, as shown.

FRANCIS E. GRUBER.
